HOLDER FOR WHETSTONES

William D. Dunn, Linden, N. J.

Application January 12, 1948, Serial No. 1,839

9 Claims. (Cl. 51-211)

1

This invention relates to holders for whet stones and it has as an object to provide such a holder which will greatly facilitate the sharpening of a tool on the whet stone held therein and which will make it possible for even an inexperienced person to produce an accurately ground cutting edge on tools, such for example, as chisels, plane blades etc.

It is well known that a great many persons are unable to maintain an even pressure on both sides of a tool blade while moving the blade over a whet stone during a sharpening operation. This inability frequently results in the wearing away of one side of the blade more than the other or the wearing away of both sides more than the center portion of the blade, thereby producing an unevenly sharpened tool.

I am aware that attempts have been made to solve this problem by providing a stone holder which will yield to uneven pressures but insofar as I am aware none of the constructions heretofore provided have been entirely satisfactory and commercially practicable.

This invention has as a primary object to provide an improved and simplified whet stone holder in which the stone is permitted to yield to unequal pressures of a tool thereon and in which the stone will have a rigid support in all of its positions, as distinguished from a resilient support, and also in which the stone will have a rolling contact with its support, as distinguished from a pivotal contact. The rolling support provided by this invention permits the stone to yield to unequal pressures and provides a control therefor which eliminates the teeter-totter action which results from a plain pivotal support.

Many whet stones, especially those known as "oil-stones," are made up of two grades of stone, one of relatively coarse grain for rapid grinding, and the other of relatively fine grain for applying a finished edge to the tool. These stones are arranged back to back so that the opposite faces of the composite stone are, respectively, coarse and fine.

Another object of this invention is to provide an improved yieldable holder for such a composite stone whereby the stone may be readily inverted, to place either face of the stone uppermost, without detaching the stone from its holder.

With the above and other objects in view, as will hereinafter appear, the invention comprises the devices, combinations, and arrangements of parts hereinafter set forth and illustrated in the

2

accompanying drawings of a preferred embodiment of the invention, from which the several features of the invention and the advantages attained thereby will be readily understood by those skilled in the art.

In the drawings,

Fig. 1 is a perspective view of my improved whet stone holder, showing a preferred form of stone-inverting means.

Fig. 2 is an enlarged side view thereof, partly broken away.

Fig. 3 is a plan view of the right end of the holder shown in Figs. 1 and 2.

Fig. 4 is a left end view of the holder with the whet stone shown, in full and in dotted lines, in two operative positions.

Fig. 5 is a left end view of the holder with the stone shown, in full and in dotted lines, in two positions through which it is passed while being inverted.

Fig. 6 is a side elevation of the right end portion of the improved stone holder showing a modified form of stone-inverting means.

Fig. 7 is a right end view of the modified construction disclosed in Fig. 6 with parts thereof shown in the position they occupy during the inversion of the stone.

Referring more specifically to the drawings, and first to the construction shown in Figs. 1 to 5, inclusive, the invention is disclosed as comprising a stamped sheet metal base including inner and outer telescopically arranged sections 1 and 2, respectively. The base section 1 is provided in its upper wall 1a with a slot 3 which is aligned with an aperture 4 in the upper wall 2a of the section 2. The sections 1 and 2 are adjustable lengthwise to accommodate stones of various lengths and are held in their adjusted positions by means of a clamp bolt 5 passing through the aperture 4 and slot 3 and having threaded thereon a wing-nut 6. Punched out of the upper walls 1a and 2a, and pressed upwardly therefrom, are standards 7 and 8, respectively, which support stone-gripping clamps 9. Each

clamp 9 comprises a sheet metal strap-like member having a rear wall 10, provided with a horizontally disposed T-shaped slot 11, and a pair of off-set curved spring arms 12 adapted to frictionally grasp the opposite side walls of a whet stone. The clamps 9 are loosely attached to the upright standards 7 and 8 by rivets 13 freely passing through apertures in said standards and through the T-shaped slots 11 in the walls 10 of the clamps. The outer head of each rivet 13 lies against the outer side of one of the standards

while the other head 13^a thereof slidingly engages the inner surface of the rear wall 10 of one of the clamps 9. As shown most clearly in Fig. 3, each clamp 9 is formed between the wall 10 and the stone gripping arms 12 with an off-set portion 14, and with a seat 15 against which one end of the whet stone abuts. The off-set portion 14 affords clearance between the end of the stone and the inner head 13^a of the rivet 13.

Punched out of and pressed upwardly from the upper walls 1^a and 2^a of the base sections 1 and 2, respectively, are convex tracks or rockers 16 upon which the lower surface of the whet stone rests in all of the various angular positions of the stone. It will be understood that as the stone rocks from side to side, in response to unequal pressures applied thereto, the stone will roll on the rockers 16 as shown, for example, in dotted lines in Fig. 4, and will not pivot on the rivets 13 which will ride up and down in the vertically disposed heads 11^a of the T-shaped slots 11. Thus the stone is permitted to yield to uneven pressures but is prevented from teetering, as it would if it were pivotally supported.

When it is desired to invert the stone, to use the other side thereof, the clamps 9 with the stone therein are lifted slightly and slid laterally from the position shown in full lines in Fig. 4 to the position shown in full lines in Fig. 5, the shanks of the rivets 13 sliding in the stems of the T-shaped slots 11. From this position the unit, comprising the clamps and the stone, is turned counterclockwise about the pivots 13 through the position shown in dotted lines in Fig. 5 to a horizontal position opposite to that shown in full lines. The unit is then slid to the right to align the rivets 13 with the heads 11^a of the T-shaped slots 11. The stone is then lowered onto the rockers 16 and is again ready for use, with the opposite face of the stone uppermost.

In the modified construction, the right end of which is shown in Figs. 6 and 7, the parts which are similar to those hereinbefore described are similarly designated. It is to be understood that the opposite end of the modified construction is similar to that shown. In this form, a standard 20 is struck up from the upper wall of each base section. Hinged at 21 to the upper end of each standard 20, by hinge pins 22, is an extension plate 23 which, as shown in full lines in Fig. 6, normally lies horizontally and below the level of the upper surface of the whet stone so as to be out of the way during a tool sharpening operation. A stone-gripping clamp 24, generally similar to the clamps 9 hereinbefore described, is mounted on each standard 20 by a rivet 25 the shank of which passes freely through a vertically disposed slot 26, formed partly in the standard 20 and partly in the hinged extension plate 23. Normally, the stone S rests upon the arcuate support 16 and rocks back and forth thereon as above described.

When it is desired to invert the stone, the stone is lifted vertically, carrying with it the clamps 24 and the rivets 25. The outer head of the rivets pass upwardly between the hinge portions 23^a of the plates 23 and cause the plates to be elevated to the position indicated in dotted lines in Fig. 6. When the shanks of the rivets 25 have reached the upper end of the slots 26 the stone S and the clamps 24 may be rotated about the axes of the rivets to invert the stone, after which it is again lowered upon the rockers 16.

From the foregoing, it will be apparent that this invention has provided a simple and inex-

pensive support for whet stones in which the stone may roll or rock to adapt itself to unequal pressures applied to opposite sides thereof and having lost-motion connections by means of which the stone readily may be inverted without removing it from its holder.

Having thus set forth the nature of the invention, what I claim herein is:

1. A whet stone holder comprising a base; a pair of stone-holding members movably mounted on said base; and at least one convexly curved member carried by said base and underlying a whet stone held in said members and affording a rolling support for said stone.
- 15 2. A whet stone holder comprising a base; a pair of standards rising from said base; a pair of stone-holding members movably mounted on said standards; and a pair of convex rockers carried by said base and affording a rolling support for a whet stone held in said members.
- 20 3. A whet stone holder comprising a lengthwise adjustable two-part sheet metal base; means for securing the two parts of the base together in adjusted positions; an upright standard struck up from each base part; a stone-gripping member movably mounted on each of said standards; and a curved rocker carried by each of said base parts and engaging the underside of a whet stone held in said members.
- 25 30 4. A whet stone holder comprising a lengthwise adjustable sheet metal base including two telescopically arranged sheet metal sections having aligned apertures; a clamp bolt passing through said apertures for securing said sections together in adjusted positions; an upright standard struck up from each of said base sections; a stone-gripping member movably mounted on each of said standards; and an arcuate rocker struck up from each of said base sections and forming a rolling support for a whet stone held in said members.
- 35 45 5. A whet stone holder comprising a sheet metal base; a pair of standards supported by said base; a sheet metal stone-holding member movably mounted on each of said standards; and a plurality of convex rockers carried by said base and forming a rolling support for a whet stone held in said members.
- 40 50 6. A whet stone holder comprising a base; a pair of standards supported by said base; a stone-gripping member mounted on each of said standards for limited vertical and horizontal movements; and a pair of convex rockers projecting upwardly from said base and engaging the underside of a whet stone held in said members and affording a rolling support for the stone.
- 55 60 7. A whet stone holder comprising a base; a pair of standards supported by said base; a stone-gripping member permanently attached to each of said standards; a pair of rockers carried by said base and normally affording a rolling support for a whet stone held in said members; and a lost motion connection between each of said members and its supporting standard to permit said members and the stone carried thereby to be shifted relative to said base and standards to an inoperative position in which said stone and members may be inverted, and thereafter returned to operative position.
- 65 70 8. A whet stone holder comprising a base; a pair of standards supported by said base; a stone-gripping member arranged in back-to-back contact with each of said standards, each of said members having formed therein a horizontally disposed T-shaped slot and each of said stand-

ards carrying a rivet passing through the slot of its associated stone-gripping member; and a pair of rockers carried by said base and forming a rolling support for a whet stone held in said members; said members and stone being shiftable laterally relative to said base, rockers and standards sufficiently to permit said stone and members to be inverted without interference with said rockers and base.

9. A whet stone holder comprising a base; a pair of standards supported by said base; a stone-gripping member permanently but loosely riveted to each of said standards; a pair of rockers carried by said base and normally affording a rolling support for a whet stone held in said members; an extension plate hinged to the upper end of

each of said standards and adapted to be swung to a position in which it projects above the upper face of said stone, said standards and their respective extension plates being formed with vertically aligned slots through which pass the rivets which secure the stone-gripping members to said standards; said slots and rivets affording lost-motion connections between said stone-gripping members and said standards to permit the members and the stone therein to be shifted to an inoperative position in which the stone and members may be inverted and thereafter returned to operative position.
